UNITED STATES PATENT OFFICE.

THEODORE B. H. VOGT, OF PASSAIC, NEW JERSEY, ASSIGNOR TO THE BRYANT ELECTRIC COMPANY, OF BRIDGEPORT, CONNECTICUT, A CORPORATION OF CONNECTICUT.

SOCKET ATTACHMENT.

Application filed July 6, 1921. Serial No. 482,730.

This invention relates to a socket attachment for electric light fixtures and has for an object the provision of a pull-chain socket adapted to be inserted in a key socket to convert the same to a pull-chain type.

A further object resides in the provision of a socket as above mentioned, which is exceedingly compact, strong and occupies much less space than sockets heretofore provided for similar purposes.

A further object resides in the provision of means whereby the socket is condensed in size and of which the economy of manufacture is greatly decreased.

A still further object resides in a construction and arrangement of parts herein-after described and claimed and shown in the accompanying drawing.

The invention in general comprises a socket of a pull-chain type to be inserted in the key socket to convert the same. Ordinarily a socket having a pull chain mechanism is exceedingly bulky and cumbersome and rather expensive to make. However, in accordance with my invention, I provide a pull-chain mechanism disposed within the socket so that the socket takes up very little, if any, more space than an ordinary convertible.

The invention is illustrated in the drawings of which—

Figure 1 is a side view of the socket.

Figure 2 is a plan view of a socket.

Figure 3 is a vertical longitudinal section.

Figures 4, 5, 6, 7 and 8 are detail views of various parts of the pull-chain mechanism.

Figure 9 is a plan view of the elements shown in Figure 7 with the elements shown in Figure 8 removed.

Figure 10 is a view taken on the line 10—10 of Figure 3, looking downward.

Figure 11 is a side view of the upper portion of the socket.

Figure 12 is a view taken on the line 10—10 of Figure 3 looking upward.

As shown in the drawings the preferred form of my invention comprises a socket member having the usual hollow insulating body portion 1, within which is disposed the usual threaded shell 2 adapted to receive the base of any electrical attachment or device, such as a lamp. In this instance the shell 2 extends upwardly beyond the up-

per edge of the body portion 1 a suitable 55 distance, and thereby is adapted to act as a threaded portion of a plug. This upper portion 3 of the shell may, therefore, be secured into any ordinary socket to transfer the electrical connections of that socket to 60 the socket formed by the lower end of the shell 2.

It is the purpose of my invention to dispose within the upper end of the shell 2 a pull-chain apparatus of any suitable type 65 so that this attachment when plugged into an ordinary key socket will permit the conversion of the combined apparatus from a key type to a pull-chain type while at the same time the attachment occupies no more space 70 than the ordinary adapter.

To this end I dispose within the upper end 3 of the shell 2 a plug of insulating material 4 having a central aperture 5. To a lower face of this plug 4 I attach, by suitable 75 means, such as screws 6, a flat ring 7 of insulating material. This ring has an inner central recess 8 which is flared downwardly as at 9. On the upper surface of the plug 4 I dispose a cup shaped member 10 80 having an annular flanged portion 11 within which a recess 12 is formed. Within this recess 12 on the top of the plug 4 is disposed an annular ring 13. This ring is made of insulating material and is provided with a 85 recess 14 in its lower face and an aperture 15. An offset portion 16 on this ring is provided with a projecting lug 17 to which one end of a chain 18 is attached. This chain extends downwardly through a groove 19 in the 90 plug 4 and a groove 20 in the ring 7. These grooves are, of course, properly aligned. The end of the groove 20 is aligned with a suitable aperture in the body portion 1 so that the free end of the chain 21 extends out from the body portion 1 to be operated by the hand of the person using the device.

A pin 22 is disposed in the recess 14, this recess normally facing downward. This pin 22 is adapted to engage with a hooked end 100 23 of a spring 24. This spring is coiled around the screw shaft 25. The other end of the spring connects to a contact plate 26, the outer end of which is bent over as at 27 to form a contact with any suitable device, such as a lamp, inserted in the socket portion 2 of the shell. The plate 26 is disposed against the upper face of the recess 105

8, and is held therein by a nut 28 on the shaft 25. The other end of the shaft is embedded in a recess 29 in the top of the cup shaped portion 10, which recess may be filled 5 with insulating material such as 30. The plug 4 and the cup shaped receptacle 10 are held in the upper end 3 of the shell 2 by any suitable means, such as screws 31. The upper surface of the ring 13 is covered by 10 a metallic contact plate 32. This plate is provided with a plurality of raised cam like finger portions 33. These fingers 33 are adapted, in the rotation of the ring 13, under the action of the chain 18, to engage with 15 cooperating edges 34 of a rotatable contact plate 35. This contact plate is provided with an aperture 36 and loosely embraces the shaft 25 above the ring 13. This contact plate is provided with upwardly and downwardly 20 extending contact fingers 37. When the ring 13 is moved in one direction by pulling downwardly on the chain, the contact plate 35 is moved. When the chain, however, is released the spring 24, the end 23 of which 25 engages the pin 22, forces the ring 13 back to a normal position. In this backward movement the cam fingers 33 slide under the engaging portions 34 of the plate 35, whereby by the plate 35 does not move on the recessional movement of the ring 13.

The contact fingers 37 on the plate 35, in one position of the plate, are adapted to make contact with terminal portions 38 turned under on the inner face of the recess 35. These terminal portions are the end portions of the integral contact strip 39; the main body portion of the strip 39 extends through to the upper central face of the cup like receptacle 10 and forms a central contact 40 surface adapted to make contact with any suitable terminal within the socket into which the plug portion 3 of the shell 2 is inserted.

It will thus be observed that I have provided a device comprising the insulating body portion 1, a socket shell 2 within said body portion, said shell extending beyond the body portion on one side thereof to form a plug portion adapted to be inserted into 45 any other socket. Furthermore, it will be observed that within the plug portion 3 of the shell 2 I have disposed all of the neces-

sary circuit connections as well as a complete pull-chain apparatus. Therefore, when this attachment is plugged into an ordinary key 55 socket, it does not take up any more space than an ordinary attachment and yet converts the socket into which it is inserted to a pull-chain socket. This economy of space with the consequent economy of manufacture is an exceedingly important one when the cumbersome and expensive attachments hitherto used for this purpose are observed. 60

What I claim is:—

1. An electric fitting comprising plug and socket areas, the plug area having a screw shell contact not exceeding standard dimensions, an insulating button at the entry end of said plug, a center contact carried by 70 said button, an insulating member spaced from the button to afford a switch chamber wholly within the screw shell contact of the plug, a switch arranged within said chamber for controlling the connection between certain of the contacts of the plug and socket areas, said switch comprising a spindle substantially coaxial with the plug area, a rotary switch member on said spindle, a ratchet member for operating the switch member, 75 and a pull member connected to said ratchet member and passing laterally from said fitting between the plug and socket areas. 80

2. An electric fitting comprising plug and socket areas, the plug area having a screw 85 shell contact not exceeding standard dimensions, an insulating button at the entry end of said plug, a center contact carried by said button, an insulating member spaced from the button to afford a switch chamber wholly 90 within the screw shell contact of the plug, a switch arranged within said chamber for controlling the connection between certain of the contacts of the plug and socket areas, said switch comprising a spindle substantially 95 coaxial with the plug area, a rotary switch member on said spindle, a ratchet member for operating the switch member, and a pull member connected to said ratchet member and passing laterally from said fitting between the plug and socket areas, together with a spirally inclined guideway for the pull member within the fitting. 100
